Patented Mar. 26, 1918.

2 SHEETS—SHEET 2,

Fig. 4.

Fig. 5.

Fig. 6.

Fig. 7.

Fig. 10.

A technical line drawing of a mechanical linkage. It features a horizontal top bar with a central slot. A vertical rod is inserted into this slot, with a small rectangular component attached to its top. A horizontal beam extends from the side of this central assembly. A vertical rod is attached to the side of the horizontal beam, and a small rectangular component is attached to its top. The drawing is annotated with several numbers: '74' is written above the top horizontal bar; '79' is written below the left end of the horizontal bar; '81' is written above the right end of the horizontal bar; '82' is written below the vertical rod attached to the horizontal beam; '83' is written to the right of the vertical rod attached to the horizontal beam; and '84' is written above the top horizontal bar, aligned with the number 74.

UNITED STATES PATENT OFFICE.

KURAKICHI SATO, OF LOS ANGELES, CALIFORNIA.

BEET-TOPPING MACHINE.

1,260,715.

Specification of Letters Patent. Patented Mar. 26, 1918.

Application filed August 27, 1917. Serial No. 188,522.

To all whom it may concern:

Be it known that I, KURAKICHI SATO, a subject of the Emperor of Japan, residing at Los Angeles, in the county of Los Angeles and State of California, have invented a new and useful Beet-Topping Machine, of which the following is a specification.

My invention relates to a machine used in the field for the purpose of topping the beets as they are dug from the ground. The principal object of my invention is to produce a machine of the class described of simple form and construction. Other objects and advantages will appear herein-
10 after from the following description.

Referring to the drawings which are for illustrative purposes only:

Figure 1 is a plan view partly in section of a machine embodying a form of my in-
20 vention.

Fig. 2 is a side elevation of the machine shown in Fig. 1, one of the wheels being removed.

Fig. 3 is a sectional view on line 3—3, Fig. 1 looking in the direction of the arrow.

Fig. 4 is an enlarged view of a portion of the front end of the machine.

Fig. 5 is a sectional view on line 5—5, Fig. 1.

Fig. 6 is a transverse sectional view on line 6—6, Fig. 1.

Fig. 7 is a cross sectional view on line 7—7, Fig. 1.

Fig. 8 is a side elevation partly in section of the pressure plates showing manner of mounting same.

Fig. 9 is a fragmentary plan view of a portion of a pressure plate and its supporting frame.

Fig. 10 is a perspective view of one of the flights of the conveyer.

11 designates a frame mounted upon front wheels 12 and rear wheels 13, the rear wheels 13 being mounted on a shaft 14 journaled in
45 suitable bearings 15 on the frame 11. 16 designates two downwardly depending posts secured in any suitable manner to the frame 11, the posts being connected by diagonally disposed timbers or braces 17 to a timber

50 18 forming part of the frame 11. 20 designates a shaft journaled in bearings 21 secured to the posts 16, which shaft 20 has secured thereto an apron 22 stiffened near its forward end by means of an angle bar 23.

55 24 designates a cutter frame, there being one such frame at each side of the apron 22.

25 designates a U bar secured in any suitable manner to the apron 22 at the forward edge of the same, and 26 designate prongs secured to the U bar 25, one prong being secured to one leg of the U bar, and the other prong being secured to the other leg of the U bar, the prongs 26 being so shaped that their forward ends are in horizontal alignment and their rear ends, where they are secured to the U bar, are in vertical alignment.

28 designates a forwardly extending supporting arm, the rear end of which is secured in any suitable manner to the front edge of the apron 22. Mounted on the top of the frame 24 in suitable bearings thereon is a shaft 30 having thereon a sprocket wheel 31 driven by a sprocket chain 32, the sprocket chain 32 being in turn driven by a 75 sprocket wheel 33 mounted on a shaft 34 which shaft 34 is supported in bearings 38 mounted on the rear end of the frame 11.

35 designates a blade or paddle formed on the end of an arm 36, the arm 36 being secured to the shaft 30 by means of a pin 37, the arm 36 and paddle thereon being designed to rotate with the shaft for purposes hereinafter described.

40 designates a gate pivotally mounted 85 at 41 to an angle bar 42, the angle bar 42 being secured in any suitable manner as by rivets 43 to one of the frames 24. The forward movement of the gate 40 is limited by a stop 44 secured to the angle bar 42, the 90 gate 40 being held elastically against such stop 44 by means of a spring 45 which is also secured to the angle bar 42.

50 designates a circular blade or primary cutting member which is secured to a shaft 95 51 mounted in a bearing 52 on one of the standards 24 said cutting member 50 being operated by means of a sprocket chain 53 which drives a sprocket wheel 54 mounted on the shaft 51, the chain 53 being in turn 100 driven by a sprocket wheel 55 mounted on the shaft 30.

57 designates a conveyer consisting of a series of flights 58 secured to a sprocket chain 59, the sprocket chain 59 passing over 105 a sprocket wheel 60 at the forward end of the conveyer and a sprocket wheel 61 at the rear end of the same, sprocket wheels 60 and 61 being secured to shafts 62 and 63 respectively, which shafts are mounted in 110 suitable bearings on the diagonal braces 17 so that the conveyer is arranged with the

forward or receiving end of the same behind the rear end of the apron 22 and extends upwardly and rearwardly to the rear end or delivery end of the conveyer. Certain of the flights 58 are provided with ribs 65 arranged diagonally upon the flight as clearly shown in Figs. 1 and 10, the rear end of the ribs 65 being cut away as indicated at 66 thereby forming a shoulder 67 on the rib.

10 The flights 58 are supported in the machine upon brackets 68 mounted upon cross bars 69 which form a part of the frame 11 of the machine. Secured to the cross bars 69 are standards 70 upon the upper ends 15 of which is secured a longitudinal extending bar 71 to which is secured a series of arms 72 and 73, which extend over the conveyer and form a support for an angle bar 74.

20 75 designates a diagonally disposed guide plate pivotally mounted at 76 to a bracket 77 mounted on the angle bar 71, the plate 75 being provided with a strap 78 which engages over the arm 72 heretofore referred 25 to. The rear end of the plate 75 extends behind a guide plate 79, the rear end of which in turn extends behind a guide plate 80, the rear end of which extends behind a guide plate 81. The arms 73 are arranged 30 in pairs as shown in Fig. 1 and each guide plate 79, 80 and 81 is provided with an upwardly extending pin 84 which extends between its associated pair of arms 73 and each guide plate 79, 80 and 81 is provided 35 with a strap 82 secured to a flange 83 on the respective plates so arranged as to engage between the strap 82 and the flange 83 a pair of the arms 73 for the purpose of movably supporting the respective plates 40 on the machine.

45 85 designates coiled springs mounted upon curved rods 86, the rods 86 extending through slots 87 in the angle bar 71 and the outer end of such rods being secured in any suitable manner to one end of the plates 79, 80 and 81. 90 designates a similar coiled spring mounted on a bar 91 which engages the rear end of the plate 81, the function of such springs being to brace the plates 50 against the root ends of the beets and thereby hold the heads of the beets against guides 95 mounted upon brackets 96 upon the frame 11.

55 98 designates a bent arm pivotally mounted at 99 to the angle bar 71, the arm 98 being curved at its forward end as indicated in the dotted lines at 100 in Fig. 2. 101 designates a circular blade or secondary cutting member secured to a shaft 102 mounted 60 in a suitable bearing 103 on the frame 11, the shaft 102 being provided with a sprocket wheel 109 driven by means of a sprocket chain 104 from a sprocket wheel 105 mounted on the shaft 34, the shaft 34 being provided with a sprocket wheel 106 driven by

a sprocket chain 107 which in turn is driven by a sprocket wheel 108 from the shaft 14.

70 The conveyer 57 is driven by means of the shaft 63 which shaft is provided with a gear 110 driven by a gear 111 mounted on the shaft 34. For the purpose of varying the vertical position of the apron 22 suitable lever mechanism 115 mounted on the frame 11 is provided which is connected by means of a link 116 with the U-bar 25.

75 In toping beets a greater amount of the head of a large beet may be cut off than may be done in the case of a smaller beet so I have provided a movable section 120 of the guides 95 elastically supported on rods 121 which pass through brackets 123 mounted on the frame 11, and provide coiled springs 122 on the rods which permits a retraction of the section 120 when a large beet is engaged by the plates 80 and 81.

80 The machine operates in the following manner:

85 The machine is driven over the ground by suitable draft means and the prongs 26 engage the beets in the ground therebetween. 90 The beets are pulled from the ground by the prongs and turned into a horizontal position due to the shape of the prongs, an arm 28 supporting the head of the beet as it reaches such horizontal position. As the 95 beet approaches the rear ends of the prongs 26 it is engaged by the paddle 35 and moved thereby against the primary cutting member 50 at which time a portion of the tops is cut off as indicated in dotted lines in Fig. 100 4. The paddle 35 presses the beet under the gate 40 causing the beet to travel over the apron 22 to the conveyer 57, the flights of which are beveled as shown at 125 in Figs. 6 and 7 to accommodate the shape of the 105 beet so that the same will lie in the machine with its major axis in approximately a horizontal position.

110 As the beet approaches the conveyer the lower end of the beet passes under the arm 98 which assists in arranging the beet in the proper position on the conveyer by pressing on the root end of the beet. As the beet travels on the conveyer rearwardly in the machine, being caught against a rib 65 on 115 one of the flights of the conveyer, the root end of the beet is engaged by diagonally disposed plate 75 which pushes the beet across the conveyer until the head of the beet is against the guides 95. The beets on the 120 conveyer are held in such position as they travel rearwardly through the machine by the spring plates 79, 80 and 81 which yield sidewise against their respective springs to accommodate the different lengths of the 125 beets and hold the heads of the same against the guides 95. The beets are held against the guides 95 until they reach the rear end of the machine and a portion of the head of the beet is cut off by the secondary cut- 130

ting member 101 after which the beets are delivered to any suitable receptacle over the discharge end of the conveyer.

The amount cut off by the secondary cutting member depends upon the length of the beet as a long beet will depress the plates 79, 80 and 81 a greater degree than a short beet and will cause a greater pressure against the elastic section 120 of the guides 95 de-
10 pressing such section and thereby cutting off a correspondingly greater amount of the head of the beet.

What I claim is:—

1. In a beet topping machine, a primary cutter arranged to cut off a portion of the tops of the beets, a secondary cutter, conveyer means for carrying the beets from the primary cutter to the secondary cutter, and means for sliding the beets across the conveyer to bring a portion of the heads of the beets into engagement with the secondary cutter.

2. In a beet topping machine, a primary cutter, means for raising beets from the ground to said cutter, a conveyer, means for moving the beets from the primary cutter to the conveyer, guide means at one side of the conveyer for the heads of the beets, means for elastically engaging the root end of the beets to slide the beets across the conveyer against the guide means, and a secondary cutter arranged to cut off a portion of the heads of the beets on the conveyer.

3. In a beet topping machine, a primary cutter, digging means for raising the beets from the ground to the primary cutter, an apron for supporting the beets, a conveyer, means for moving the beets from the apron to the conveyer, and a secondary cutter ar-
40 ranged to cut the beets on the conveyer.

4. In a beet topping machine, a primary cutter, digging means for raising the beets from the ground to the primary cutter, an apron for supporting the beets, a conveyer,
45 means for moving the beets from the apron to the conveyer, means for elastically mov-

ing the beets across the conveyer, and a secondary cutter arranged to cut the beets on the conveyer.

5. In a beet topping machine, a primary cutter, digging means for raising the beets from the ground to the primary cutter, an apron for supporting the beets, a conveyer, means for moving the beets from the apron to the conveyer, guides for the heads of the beets at one side of the conveyer, a diagonally disposed plate over the conveyer arranged to move the beets sidewise across the conveyer, a series of plates forming a continuation of said diagonally disposed plate adapted to elastically hold the beets against the guides, and a secondary cutter at one side of the conveyer for cutting the beets thereon.

6. In a beet topping machine, a primary cutter, digging means for raising the beets from the ground to the primary cutter, an apron for supporting the beets, an elastically retained gate above the apron, a paddle arranged to move the beets through the gate over the apron, a conveyer, guides for the heads of the beets at one side of the conveyer, means for elastically moving beets sidewise on the conveyer against said guides, and a secondary cutter at one side of the conveyer for cutting the beets thereon.

7. In a beet topping machine, a primary cutter, digging means for raising the beets from the ground to the primary cutter, an apron for supporting the beets, a conveyer, means for moving the beets from the apron to the conveyer, guides for the heads of the beets at one side of the conveyer, means for elastically moving the beets sidewise on the conveyer against said guides, a secondary cutter at one side of the conveyer, and a yielding section formed as part of said guides adjacent the secondary cutter.

In testimony whereof, I have hereunto set my hand at Los Angeles, California, this 17th day of August, 1917.

KURAKICHI SATO.
